Victor J. Evans
ATTORNEY

UNITED STATES PATENT OFFICE

OSCAR MICHAUD, OF SALEM, MASSACHUSETTS

KNIFE FOR CUTTING SHOES

Application filed May 2, 1930. Serial No. 449,288.

My present invention has reference to what is commonly termed a knife for cutting shoes, that is, a knife for cutting the parts, which include the linings that constitute the upper of a shoe, and my invention is in the nature of a gage attachment for such knives, whereby different sizes of vamps and quarters including linings may be cut by a single knife from a single pattern.

10 A further object is the provision of an attachment for this purpose which shall be of an extremely simple construction, readily attached to the ferrule of the knife and having associated therewith gage discs arranged to the opposite sides of the knife and movable to contact with the strips to be cut by the knife, together with means for holding a desired number of such gage discs above those contacting the strips so that the 15 knife can be held at a proper and desired distance from the edges of the pattern and whereby the parts constituting the shoe uppers may be cut in different sizes by the employment of a single pattern.

20 25 To the attainment of the foregoing the invention consists in the improvement hereinafter described and definitely claimed.

In the drawings:

Figure 1 is a side elevation of the improvement.

Figure 2 is a top plan view thereof.

Figure 3 is a sectional view approximately on the line 3—3 of Figure 1.

Figure 4 is an end view of the frame of 35 the improvement.

Figure 5 is a plan view of one of the gage discs.

Figure 6 is a plan view of a pattern, the dotted lines indicating the cut made by the 40 knife when a vamp or quarter of a determined size is required.

Referring now to the drawings in detail, the numeral 1 designates the handle of an ordinary knife for cutting shoes and the 45 curved cutting blade which is secured to the handle is indicated by the numeral 2.

The knife is of the ordinary construction, and in carrying out my invention I arrange over the ferrule end of the handle and fixedly but preferably removably secure thereto

the ring or collar member 3 of the frame of the improvement. From the ring or collar, which constitutes the body of the frame, there is extended side arms 4 which are arranged at upward angles with respect to the 55 longitudinal plane of the handle and which have their outer ends formed with right angularly disposed downwardly arranged extensions 5. The sides of the frame are arranged at a suitable distance away from 60 the sides of the knife, and the outer elements 5 of the frame are provided with upper and lower alining square or rectangular openings 6 and 7, respectively. Through these alining pairs of openings there are 65 passed square or rectangular shanks of headed members, in the nature of pins or studs 8 and 9, respectively. The shank of the upper stud 8 has an opening therethrough in a line with one of the side members of 70 the frame and through this opening there is passed the inner arm of a substantially U-shaped spring clip 10, the outer arm of the clip contacting with the outer end of the stud 8. The non-headed end of the 75 lower stud 9 is threaded and has screwed thereon a nut 11 which contacts with one of the side members of the frame.

Any desired number of gage discs 12 may be employed but an equal number of such 80 discs are arranged at each side of the knife 2. The discs also are of an equal size and thickness and each of the discs is provided with a central elongated slot or opening 13 of a size to receive therethrough the 85 shanks of the studs 8 and 9.

A pattern from which the strips that constitute the upper of a shoe are to be cut is disclosed by Figure 6 of the drawings and is indicated by the numeral 14. This 90 pattern is for cutting the upper of a small size of a shoe and when the strips 15 that constitute the parts of the upper and the lining are positioned below the pattern and the pattern firmly secured thereon all of 95 the gage discs are engaged by both the studs 8 and 9 so that the blade of the knife may be brought against the edges of the pattern. When strips for the next size upper of a shoe are required all of the discs, except 100

those directly adjacent the blade of the knife are retained elevated but the said inner discs are lowered so that they will have their lower edges contacting with the 5 upper strip 15. This is accomplished by removing the studs 8 and 9 so that the mentioned inner discs may be lowered on the shank of the stud 9, the remaining discs being held elevated after the studs are replaced. 10 By reference to Figure 3 of the drawings it will be noted that the lower edge of the upper stud 8 is in contact with the upper periphery of the lower gage discs so that such lowered discs are firmly sustained in 15 proper position. The discs, instead of the knives are now brought against the edges of the pattern 14 in the cutting operation. By arranging the discs on each side of the knife a firm pressure against the strips 15 20 is afforded and in addition to this the knife may be reversed for the convenience of the operator in following the outline of the pattern during the cutting operation. When larger sizes of vamps or quarters and lin- 25 ings are required other discs are brought to lowered position and thereby increasing the distance between the edge of the pattern and the knife 2. Thus it will be noted that with my simple construction single patterns 30 of a small size may be employed and also a single knife is used for cutting the uppers of any desired size of shoe.

It is believed the foregoing description when carefully read in connection with the 35 accompanying drawings will fully set forth the simplicity of my device and the advantages thereof so that further description will not be required. Obviously I do not wish to be restricted to the precise details herein 40 set forth and, therefore, hold myself entitled to make such changes therefrom as fairly fall within the scope of what I claim.

Having described the invention, I claim:

1. A knife for cutting the uppers and lin- 45 ings of shoes, in which a pattern of a de- termined size is arranged over the strips to be cut, of a frame secured to the ferrule of a knife handle and comprising upwardly inclined sides that merge into rightangular 50 downwardly extended ends, upper and lower removable studs passed through the outer ends of the frame, slotted gage discs sup- ported by the studs, said discs being adapt- ed to be selectively arranged on the lower 55 stud or receiving both studs therethrough, and the discs when on the lower stud being contacted by the upper stud.

2. A knife for cutting the uppers and lin- 60 ings of shoes, in which a pattern of a de- termined size is arranged over the strips to be cut, of a frame comprising a ring member surrounding and fixed to the ferrule of the handle of the knife, upwardly inclined arms extending from the sides of the 65 ring member merging into right angularly

arranged downwardly directed arms which are provided with upper and lower alining rectangular openings, headed studs having rectangular shanks passing through the openings, a spring clip for holding the outer stud on the frame, a nut screwed on the lower stud for holding the same on the frame, centrally slotted gage discs all of an equal size and thickness designed to receive the shanks of the studs there- 70 through and which discs are arranged in equal numbers at the opposite sides of the knife blade, said disks being adapted to be selectively supported by both of the studs or supported by the lower stud and the discs when on the lower stud being contacted by the upper studs.

In testimony whereof I affix my signature.
OSCAR MICHAUD.
